UNITED STATES PATENT OFFICE.

RHENIER S. MASON, OF EDDYVILLE, KENTUCKY.

HORSE-COLLAR.

1,155,943.

Specification of Letters Patent.

Patented Oct. 5, 1915.

Application filed June 6, 1913. Serial No. 772,162.

To all whom it may concern:

Be it known that I, RHENIER S. MASON, a citizen of the United States, residing at Eddyville, in the county of Lyon and State of Kentucky, have invented new and useful Improvements in Horse-Collars, of which the following is a specification.

The present invention relates to improvements in horse collars, the object of the same being to construct a collar of this class which will readily adjust itself upon the necks of horses of various sizes as well as to protect the neck, throat and shoulders of the animal after any of the said parts have become injured by the use of the ordinary collar, or from other causes.

For a full and comprehensive understanding of the improvement, reference is to be had to the accompanying drawings in which there is illustrated a simple and preferred embodiment of the improvement reduced to practice.

In the drawings, Figure 1 is a view of the rear of my improved collar, Fig. 2 is a transverse sectional view on the line 2—2 of Fig. 1, Fig. 3 is a similar sectional view on the line 3—3 of Fig. 1, Fig. 4 is a sectional view on the line 4—4 of Fig. 1, and Fig. 5 is a vertical transverse sectional view on the line 5—5 of Fig. 1.

The improved collar is broadly indicated by the numeral 1.

The rim or fore-wale 2 of the collar, is constructed of firm leather and is merely of uniform size and shape in cross section throughout its length. The rim 2 is compactly filled with long, strong, coarse fiber 2' to render the rim sufficiently strong and firm for supporting the parts of the after-wale.

The after-wale includes a face or liner 4 of strong, soft leather which is preferably continuous throughout the length of the side halves and the throat of the collar. The liner 4 has its edges stitched by a closing seam A to the inner edges of the rim 2, while the outer edges of the liner are secured by a thread stitch closing seam B to the outer edges of the firm leather which extends from the rim proper and provides the outer face of the after-wale. The face or liner 4, when stitched, as above described, to the rim and to the outer edge of the firm leather or after-wale proper, provides a pocket to receive a filling 6 of soft yieldable fiber.

The liner 4 is drawn inwardly from its edge stitches and again fastened to the outer stiff or firm leather face of the collar by an inner ribbon thong seam 7 and an outer ribbon thong seam 7'. The thong seam 7, at the top or sweeny portion of the collar is arranged at a suitable distance from the inner closing seam A, and the outer thong seam 7' is arranged inwardly of, but almost in the same plane with, the outer thread stitch closing seam B, so that the fiber filling, at these portions of the collar bulge the liner outwardly so that the same is approximately semi-circular in cross section, providing the same with what I term rolls and which are designated by the character C. The inner thong seam 7 opposite the shoulder draft or crooks of the collar is arranged in an outwardly curved line, toward the rim 2, and is continued in a line with the inner closing seam A, while the outer ribbon thong seam 7' is continued in the same plane, or approximately so, with relation to the outer closing seam B or the edges of the after-wales. The fiber 6, as stated, entirely fills the pocket provided between the liner 4 and the outer faces of the after-wales, the said filler bulging or flaring the liner 4 outwardly from the rolls C providing the liner with bellied portions D. It should be stated that the liner at the belly D is of a greater width than at any other portion thereof, so that the inner or opposite rounded edges of the bellies extend inwardly of the side halves of the collar over the rim 2. The inner edges of the bellies are curved gracefully from the rolls C, and the inner thong seam 7, at the throat of the collar follows the curvature of the said throat, or the curvature of the rim 2 at the throat, but is disposed centrally below the closing seam A at this portion of the collar. The outer thong seams 7' at the lower portion of the bellies D is arranged inwardly at a curve, as is designated particularly by the numerals 7'', and is from thence continued downwardly at an inward curvature providing the facing or liner 4 with a roll 8 at the throat of the collar. The curved portions 7'' of the outer thong seam 7' causes the inner or adjacent edges of the bellies D to be projected beyond the inner edges of the rim 2, and the space or unfilled portions of the inner liner 4 between the said seams 7'' and the outer edge of the shoulder draft or crooked portions of the collar provide hollow portions upon the

2
 collar which are disposed opposite the upper portions of the fore-thigh, or elbows of the draft animal to which the collar is applied, relieving this portion of the animal from continuous contact with the collar, and so preventing the lamining of the animal at these points. It should here be stated that these parts of the animal are most susceptible to injury from a collar and injury thereto not infrequently results in the total disabling of the animal.

It is, of course, to be understood that my collar is to be constructed in various sizes to accommodate various sizes of draft animals, and preferably the collar has an open top which is connected by the usual strap and buckle, a protector pad 5 underlying the meeting edges of the top. When the collar is arranged upon the neck of an animal 15 the rolls C are arranged to fit the opposite sides of his withers, the throat roll 8 contacts with his chest at a suitable distance below his neck, so as not to interfere with the breathing of the animal, while the belly portions D engage with the shoulder portion of the animal directly above his chest, and at points best formed by nature to withstand the greatest amount of strain. When the hames are applied to the collar the draft 20 will be directed from the enlarged or bellied portions of the face or liner 4, the portions C and 8 will roll by contact with the animal to properly position the bellied portion D and so prevent the galling or scraping at 25 the neck or withers of the animal.

From the above description, taken in connection with the accompanying drawings, the simplicity of the device, as well as the advantages of the device will, it is thought, 30 be perfectly apparent to those skilled in the art to which such invention appertains without further detailed description.

Having thus described the invention, what I claim as new is:

45 1. A horse collar including a fore-wale of firm leather, an after-wale having an outer facing of firm leather formed with the fore-wale and an inner face or liner of soft material, the said liner having its edges stitched 50 to the inner edges of the fore-wale and the outer edges of the outer facing, the said liner being further secured to the outer facing by an inner and an outer seam, provid-

ing the central portion of the liner and the central portion of the outer facing with a 55 pocket, and a filler of soft fiber for the pocket, said liner being approximately semi-cylindrical in cross section at the top sides of the collar and having widened belly portions opposite the shoulder draft or crooks 60 of the collar, the said bellies having their inner opposite portions projecting beyond the inner edges of the fore-wale, and the lower portions of the bellies to the outer sides thereof being arranged at an inward curvature a 65 distance away from the outer edges of the after-wale greater than at any other portion at which the liner is connected with the outer facing of the collar.

2. A horse collar including a fore-wale 70 and an after-wale comprising an outer facing and an inner liner which is stitched to the outer facing, a fiber packing between the liner and facing arranged to form upper rolled portions and a belly portion arranged 75 below each of the rolls and opposite the shoulder draft portion of the collar, the said belly portions inclining outwardly from the rolls and inwardly with respect to the fore-wale, the said belly portions having their 80 lower edges rounded inwardly to provide depressions in the liner, the said liner having a reduced portion which is arranged at the throat of the collar below the fore-wale and above the outer edge of the collar. 85

3. A horse collar including a fore-wale and an after-wale, said after-wale comprising an outer facing and an inner liner, and said liner being stitched to the outer facing and to the fore-wale, a packing between the 90 liner and facing arranged to form upper rolled portions and a belly portion arranged below each of the rolls and opposite the shoulder draft of the collar, the said belly portions inclining outwardly from the rolls 95 and inwardly with respect to the fore-wale, and the said belly portions having their lower portions rounded inwardly to provide depressions in the facing and in the liner.

In testimony whereof I affix my signature 100 in presence of two witnesses.
